UNITED STATES PATENT OFFICE

154,673

DESIGN FOR A COMBINED TWIN FRYING PAN AND GRIDDLE

Arthur R. Glidden, Seattle, Wash.

Application April 2, 1947, Serial No. 138,115

Term of patent 7 years

(Cl. D44—1)

To all whom it may concern:

Be it known that I, Arthur R. Glidden, a citizen of the United States and a resident of Seattle, in the county of King and State of Washington, have invented a new, original, and ornamental Design for a Combined Twin Frying Pan and Griddle, of which the following is a specification, reference being had to the accompanying drawing, forming a part thereof:

In said drawing, the single figure is a perspective view showing my new design for a combined twin frying pan and griddle.

I claim:

The ornamental design for a combined twin frying pan and griddle, as shown.

ARTHUR R. GLIDDEN.
